(57) **CLAIM**

An ornamental design for a sear assembly for a striker fired handgun, as shown and described.

DESCRIPTION

FIG. 1 is a top perspective view of our new design of a sear assembly for a striker fired handgun;

FIG. 2 is a front, bottom perspective view of the sear assembly of FIG. 1;

FIG. 3 is a back, bottom rear perspective view of the sear assembly of FIG. 1;

FIG. 4 is a front, left side perspective view of the sear assembly of FIG. 1;

FIG. 5 is an front, right side perspective view of the sear assembly of FIG. 1;

FIG. 6 is an alternate back, bottom perspective view of the sear assembly of FIG. 1;

FIG. 7 is a bottom view of the sear assembly of FIG. 1;

FIG. 8 is a back, right side perspective view of the sear assembly of FIG. 1;

FIG. 9 is an alternative front, right side perspective view of the sear assembly of FIG. 1;

FIG. 10 is a back, left side perspective view of the sear assembly of FIG. 1;

FIG. 11 is a front view of the sear assembly of FIG. 1;

FIG. 12 is an alternative bottom view of the sear assembly of FIG. 1;

FIG. 13 is an alternative bottom view of the sear assembly of FIG. 1;

FIG. 14 is a left side view of the sear assembly of FIG. 1;

FIG. 15 is a right side view of the sear assembly of FIG. 1;

FIG. 16 is an alternative top, back, left side perspective view of the sear assembly of FIG. 1;

FIG. 17 is an alternative bottom, front perspective view of the sear assembly of FIG. 1; and,

FIG. 18 is an alternative front, left side perspective view of the sear assembly of FIG. 1.
